US00D931402S

(12) **United States Design Patent** (10) **Patent No.:** **US D931,402 S**
Brittingham et al. (45) **Date of Patent:** **** Sep. 21, 2021**

(54) **SUPPRESSOR TOOL**

(71) Applicant: **Q, LLC**, Portsmouth, NH (US)

(72) Inventors: **Kevin Brittingham**, Portsmouth, NH (US); **Ethan Lessard**, East Kingston, NH (US); **Brian McDonald**, Portsmouth, NH (US)

(73) Assignee: **Q, LLC**, Portsmouth, NH (US)

(**) Term: **15 Years**

(21) Appl. No.: **29/739,398**

(22) Filed: **Jun. 25, 2020**

Related U.S. Application Data

(62) Division of application No. 29/707,929, filed on Oct. 2, 2019, now Pat. No. Des. 898,857, which is a division of application No. 29/603,015, filed on May 5, 2017, now Pat. No. Des. 867,511.

(57) **CLAIM**

The ornamental design for a suppressor tool, as shown and described.

DESCRIPTION

FIG. 1 is an isometric view of a suppressor tool according to the present disclosure;

FIG. 2 is an isometric view of an open configuration of the suppressor tool of FIG. 1;

FIG. 3 is a front view of the suppressor tool of FIG. 1;

FIG. 4 is a rear view of the suppressor tool of FIG. 1;

FIG. 5 is a right side view of the suppressor tool of FIG. 1;

FIG. 6 is a left side view of the suppressor tool of FIG. 1;

FIG. 7 is a top view of the suppressor tool of FIG. 1;

FIG. 8 is a bottom view of the suppressor tool of FIG. 1;

FIG. 9 is an isometric view of the suppressor tool of FIG. 1 in an environment of use;

FIG. 10 is an isometric view of the suppressor tool of FIG. 1 in an environment of use; and,

FIG. 11 is an isometric view of the suppressor tool of FIG. 1 in an environment of use.

The broken lines in the Figures illustrate portions of the article and environmental structure that form no part of the claimed design.

1 Claim, 6 Drawing Sheets
